RECEPTACLE FOR GRANULAR OR PULVERULENT CONDIMENTS FOR TABLE USE

Charles Reginald Langton, London, England

Application July 16, 1932, Serial No. 622,952, and
in Czechoslovakia July 22, 1931

4 Claims. (Cl. 65—45)

This invention is for improvements in receptacles for granular or pulverulent condiments for table use. Receptacles according to the invention are primarily intended for containing salt but can be used for other condiments, for example pepper or sugar. The object of the invention is to provide improved constructions of such receptacles and consists in certain novel features of construction which will be herein-
10 after described and claimed.

According to one feature of the invention, there is provided a receptacle for the purpose set forth comprising an upstanding wall, an opening in said wall near its upper end, and an inverted trough which extends outwardly from that wall and is arranged above the opening so as to constitute, when the receptacle is inverted, a chute leading to said opening for facilitating the charging of the receptacle.

15 Receptacles according to the invention may be of various forms, for instance they may comprise a rectangular body part and a roof of inverted trough shape in cross-section, the body part having an end wall that terminates below the apex of the roof to provide, between the upper edge of that wall and the roof, the opening aforesaid, which roof extends beyond said end wall and serves, when the receptacle is inverted, as the chute aforesaid.

20 The receptacles may be made of any suitable material, for instance glass or earthenware, and may be of any desired shape, for instance they may be constructed to simulate a cottage or other building.

25 The accompanying drawing shows by way of example, a receptacle according to the invention made of pottery and suitable for containing salt. In the drawing:—

30 Figure 1 is a longitudinal sectional elevation of the receptacle; and

35 Figure 2 is a perspective view thereof in the charging position.

The receptacle is formed to simulate a substantially rectangular single story cottage having two end walls 10, 11 and a roof 12 of inverted trough shape in cross section which closes the top of the receptacle and extends beyond the end walls. The upper end of the wall 10 terminates in a horizontal edge 13 so as to provide an opening 14 between it and the sloping sides of the roof. When the receptacle is inverted, as shown in Figure 2, the sloping sides of the roof constitute a chute leading to the opening 14, and permit salt to be easily poured into the receptacle. By tilting the receptacle from its normal position salt can be poured out of the opening 14. To facilitate this, the inner face of the wall 10 slopes towards the opening as shown at 14. The opening 14 thus

serves both as the charging inlet and the discharging outlet.

From the foregoing it will be appreciated that in constructions according to the invention the necessity of providing for the charging opening, corks or other removable closures liable to be mislaid or inadvertently pushed into the receptacle is obviated.

The invention is not restricted to the specific construction shown in the drawing. For instance, when the receptacle is intended to contain sugar, it may be desirable to provide more than one opening serving for both charging and discharging purposes. Further, the receptacles may be of any convenient shape.

I claim:

1. A receptacle for granular or pulverulent condiments for table use, comprising a rectangular body part and a roof of inverted trough shape in cross section, said body part having an end wall that terminates below the apex of the roof to provide, between its upper edge and the roof, an opening to serve for both charging and discharging purposes, which roof extends beyond said end wall.

2. A receptacle for granular or pulverulent condiments for table use, comprising a rectangular body part and a roof of inverted trough shape in cross section, said body part having an end wall that terminates below the apex of the roof to provide, between its upper edge and the roof, an opening to serve for both charging and discharging purposes, the inner face of which end wall slopes from the bottom of the receptacle towards the opening aforesaid.

3. A receptacle for granular or pulverulent condiments for table use comprising two side walls, two end walls and a roof of inverted trough shape in cross section that extends beyond one end wall, which wall terminates below the apex of the roof to provide an opening for charging and discharging purposes and has an inner face which slopes from the bottom of the receptacle towards said opening.

4. A closed receptacle for granular or pulverulent condiments for table use, comprising an upstanding wall, an opening in said wall near its upper end, and an inverted trough which extends outwardly from that wall and is arranged above the opening so as to constitute, when the receptacle is inverted, a chute leading to said opening.

CHARLES REGINALD LANGTON.
